IVY ATWOOD PUTNAM, OF MEXICO, MAINE.

Letters Patent No. 77,212, dated April 28, 1868; antedated April 18, 1868.

IMPROVED CHUTE FOR RIVER-NAVIGATION.

The Schedule referred to in these Letters Patent and making part of the same.

TO ALL WHOM IT MAY CONCERN:

Be it known that I, Ivy Atwood PUTNAM, of Mexico, in the county of Oxford, and State of Maine, have invented a new and improved Boat-Chute for River-Navigation, of which the following is a full, clear, and exact description, reference being had to the accompanying drawings, in which—

Figure 1 represents a sectional view of a boat-chute and dam, and

Figure 2 is a plan view of the same.

The object of my invention is to render rivers, at points where the water is apt to be shallow, at all times (except when closed by ice) accessible to the transportation of flat-bottomed boats, both up and down stream.

On the uplands of our western rivers in particular, and where canal and railroad communication is out of reach, are waste treasures of minerals, coals, wood, cereals, and other products, which are prevented from reaching a convenient market at seasonable time, on account of the low state of water not permitting boats to pass the shoals, sand-bars, or rocky places in those rivers. The river-beds are of unequal depth, which renders the navigation upon them, combined with the frequent changes in the height of the water, extremely difficult, and frequently almost impossible, stopping for a time all water-transportation. At one part of the river there may be a depth of thirty to forty feet; then, again, for a short intervening space, over rocks or shoals, the depth may be only six to eighteen inches.

My invention consists in constructing a chute or canal, of sufficient width to admit of the passage of only one boat, the sides of the said chute being enclosed to a height of from eighteen to twenty-four inches, or to any height required, by a dam, which may be built across the river on the upper end of the chute.

In all shallow places, or where irregularities in the flow of water occur, the river generally widens to a greater or less extent. The dam which I propose to build being not over twenty-four inches in height, contracts the water-space, and compels the water to pass through the chute as the only outlet. This will happen at ordinary and extraordinary low water. The water, when ordinarily low, should reach the top of the dam, and when extraordinarily low, will just reach the bed of the chute, and flow down the incline.

The chute consists of a structure of stone or timber, (worthless wood, such as cotton-wood, may be used to advantage,) laid at an inclination down the river, and embedded in the surface of the shoals, &c.; the sides of the chute being of the same relative height as the dam, and having its ends bevelled off, so as to facilitate the entrance of the boat both above and below. Rollers made of iron or wood may be arranged across the chute, and partially under the surface of the same, for the purpose of facilitating the passage of the boat up or down the chute. The rollers are set sufficiently far apart to allow the boat to rest on two or more sets.

When going up stream, a capstan or windlass, worked by hand, horse, or steam-power, may be applied to pull the boat up the chute. At each end of the chute, buoys may be anchored, to guide the boat to the chute, in case the water is deep enough to cover the same.

Referring to the drawings, *aa* represents the substructure of the chute, formed of logs or planks of wood, arranged in a position inclining down the stream, and secured in any suitable manner. *bb* represent rollers, inserted at intervals in the same, and extending sufficiently above the surface of the chute to sustain a boat passing over the same. These rollers may be made of wood or iron. At each side of the chute are built walls, *cc*, of sufficient height to contain enough water to float the boat. The said walls may be made of wood, stone, or other material. At the upper end of each wall or side is a dam, *d*, extending at any desired angle from the same, and serving to direct the water to the chute. *ff* are buoys, anchored near the upper and lower ends of the chute, to indicate the position of the same when covered by the water. *e* is the boat, in the act of passing over the chute.

The chute may be built in the middle, or at either side of the bed of the river.

What I claim as my invention, and desire to secure by Letters Patent, is—

The construction of a chute for the passage of boats over the shallow or rocky parts or rapids of a river, in the manner substantially as specified.

In testimony whereof, I have signed my name to this specification in the presence of two subscribing witnesses.

I. ATWOOD PUTNAM.
